CLAIM

The ornamental design for a cellular phone case, as shown and described.

DESCRIPTION

FIG. 1 is a perspective view of the inventive design for a cellular phone case;

FIG. 2 is a front elevational view thereof;

FIG. 3 is a rear elevational view thereof;

FIG. 4 is a side elevational view thereof;

FIG. 5 is a side elevational view thereof;

FIG. 6 is a bottom elevational view thereof;

FIG. 7 is top elevational view thereof; and,

FIG. 8 is a perspective view thereof illustrating the inventive design for a cellular phone case in its opened condition.

The broken line showing of an antenna is for illustrative purposes only and forms no part of the claimed design.
